QUILTING FRAME

Edward Broeker, Norfolk, Nebr.

Application November 14, 1934, Serial No. 753,052

6 Claims. (Cl. 45—24)

The present invention relates to a quilting frame and has for its object to provide a structure wherein the frame may be tilted either way when not in use or can be left stationary.

Another very important object of the invention is the provision of a quilting frame of this nature which will take up comparatively little space when not in use.

A still further important object of the invention resides in the provision of a quilting frame of this nature which is exceedingly simple in construction, inexpensive to manufacture, easy to manipulate and adjust, thoroughly efficient and reliable in use, and otherwise well adapted to the purpose for which it is designed.

With the above and numerous other objects in view as will appear as the description proceeds, the invention consists in certain novel features of construction, and in the combination and arrangement of parts as will be hereinafter more fully described and claimed.

In the drawings:

Figure 1 is a top plan view of the quilting frame embodying the features of my invention,

Figure 2 is a side elevation thereof,

Figure 3 is an end elevation thereof,

Figure 4 is a detailed vertical transverse section thereof, and

Figure 5 is a fragmentary perspective view of the upper end of one of the standards.

Referring to the drawings in detail it will be seen that the numerals 5, 5 denote a pair of vertical standards rising from inverted U-shaped like legs 6 and the upper ends of the standards 5 are provided with pairs of notches 7. The notches of each pair are arcuate curving upwardly toward each other and each notch gradually increases upwardly in width. The spaces between the notches of each pair are of a distance substantially equal to the width between the pairs of stud bolts projecting from the end rails of the frame as will hereafter appear. A brace 8 extends between the intermediate portions of the standards 5 and the ends thereof are bolted to the standards by the wing bolts 9.

The frame consists of a pair of end rails or cross bars 10, 10 in the ends of which are journaled the shafts 11, 11 which extend transversely with respect to the cross bars 10, 10. Mounted on the shafts are the rollers or drums 12 which rotate with shaft 11. The brake disks or wheels 14 are mounted on the ends of the drums to the inside of the bars 10. There is a brake finger 15 for each of the four wheels 14, and each brake finger is pivoted on a pin 15a to

swing on the inner faces of the bars to engage with the edge of the brake disks or wheels 14. For this purpose the outer edges of the brake fingers 15 are curved and provided with a roughened surface 20. The roughened curved surface is sufficient to hold the rollers or drums 12 in any desired position during the weaving operation by pulling up on the free end of the brake fingers 15.

The rails 10 are provided with spaced stud bolts 16, there being two stud bolts projecting outwardly from each bar in spaced relation equidistant from the center of the bar. The pairs of stud bolts are received in the notches 7 and thumb nuts 17 are engaged therewith so as to hold the frame at different tilted positions when the thumb nuts are tightened. The curvature of the notches facilitates the reception of the stud bolts and permits the frame to be readily tilted.

As is customary in quilting there is usually a foundation web 18 secured to the rollers 12 on which the quilt is made. It is desirable to maintain the web firm while quilting yet it is necessary to move the web from time to time as the work progresses. By having the braking arrangement of the present invention the web will be held firm when brake fingers 15 engage the brake disks 14, and at the same time movement of the brake finger will release the brake and permit delicate movement of the web.

It is thought that the construction, operation, utility and advantages of this invention will now be quite apparent to those skilled in this art without a more detailed description thereof.

Having thus described my invention, what I claim as new is:

1. An apparatus of the class described comprising a pair of uprights disposed in spaced vertical parallel coextensive relationship and having the upper ends thereof formed each with a pair of spaced notches curving upwardly and inwardly toward each other, and a quilting frame having stud bolts projecting therefrom outwardly, a pair at each end, for resting in and movement in the notches, and nuts engaged on the ends of the stud bolts.

2. An apparatus of the class described comprising a pair of uprights disposed in spaced vertical parallel coextensive relationship and having the upper ends thereof formed each with a pair of spaced notches curving upwardly and inwardly toward each other, and a quilting frame having stud bolts projecting therefrom outwardly, a pair at each end, for resting in and movement in the notches, nuts engaged on the ends of the stud bolts, and a brace extending be-

tween intermediate portions of the uprights and bolted thereto.

3. An apparatus of the class described comprising a pair of uprights disposed in spaced vertical parallel coextensive relationship and having the upper ends thereof formed each with a pair of spaced notches curving upwardly and inwardly toward each other, and a quilting frame having stud bolts projecting therefrom outwardly, a pair 10 at each end, for resting in and movement in the notches, nuts engaged on the ends of the stud bolts, a brace extending between intermediate portions of the uprights and bolted thereto, and inverted U-shaped like legs secured to the bottom ends of the uprights.

4. An apparatus of the class described comprising a pair of uprights disposed in spaced vertical parallel coextensive relationship and having the upper ends thereof formed each with a pair 20 of spaced notches curving upwardly and inwardly toward each other, and a quilting frame having stud bolts projecting therefrom outwardly, a pair at each end, for resting in and movement in the notches, nuts engaged on the ends of the stud bolts, each frame comprising a pair of end cross bars from which the studs project outwardly, a pair of shafts journaled between the 25 ends of the bars, drums on the shafts, brake

wheels on the shafts, and brake fingers pivoted on the bars for engagement with the brake wheels.

5. An apparatus of the class described comprising a pair of spaced upright supports each one of which is formed with a pair of spaced bearing notches with the individual notches in one pair in alignment with the corresponding notches in the other pair, a quilting frame having a pair of spaced trunnions on each side 10 thereof for resting in and movable into and out of the notches to allow the frame to rock in two directions, and coacting means carried by the frame and engageable with the supports for locking the frame stationary with respect to the supports in any desired position. 15

6. An apparatus of the class described comprising a pair of spaced upright supports each one of which is formed with a pair of spaced bearing notches, a quilting frame having a pair 20 of spaced trunnions on each side thereof for resting in and movable into and out of the notches to allow the frame to rock in two directions, and coacting means carried by the frame and engageable with the supports for locking the 25 frame stationary with respect to the supports in any desired position.

EDWARD BROEKER.
